UNITED STATES PATENT OFFICE.

ROBERT V. BINGAY, OF PITTSBURGH, PENNSYLVANIA, ASSIGNEE TO PITTSBURGH TRANSFORMER COMPANY, A CORPORATION OF PENNSYLVANIA.

TRANSFORMER.

Application filed August 11, 1920. Serial No. 402,840.

To all whom it may concern:

Be it known that I, ROBERT V. BINGAY, a citizen of the United States, residing at Pittsburgh, in the county of Allegheny and State of Pennsylvania, have invented certain new and useful Improvements in Transformers, of which the following is a specification.

This invention relates to transformers and particularly to transformers cooled by a ventilating fluid such as oil.

Although this application discloses features of invention described and claimed in my pending application, Serial No. 331,325, filed Oct. 17, 1919, this application is directed to disclosures and claims not contained in said earlier application.

The object of this invention is to provide a transformer particularly of the double magnetic circuit or shell type core in which the coil windings are formed to have a large surface exposed to the cooling action of the ventilating fluid, and to transmit this cooling effect to the less exposed portions so that a greater current density in the copper conductors is available without excessive temperature rise.

A further object of the invention is to maintain the symmetry and strength of the winding and use the most efficient form of core while thus increasing the cooling effect.

In the embodiment of the invention illustrated in the drawing,

Fig. 1 is a plan view in horizontal section of an oil cooled transformer;

Fig. 2 is a view of the transformer in elevation;

Fig. 3 is a view on enlarged scale of a portion of Fig. 1, and

Fig. 4 is a detail view of a portion of the transformer winding.

The transformer shown has a double magnetic circuit or shell type core R with the coil C around its central leg and having its ends c overhanging the core at each side. The convolutions of the coil C at each end c are wound with continuous curvature so that each convolution is arch shaped as viewed in section. The coil is made oblong, oval or elliptical in section or of general elliptical or oval form and the core legs as seen in section have a greater depth than width minimizing the overall width of core. The laminations of the core R are in planes

parallel to the line a (Fig. 1) and substantially at right angles to the major axis of the elliptical section of the coil C.

The transformer is placed in oil in a tank T and the circulation of the oil upward along the transformer surfaces and downward along the sides of the tank cools the coils and core. The ends c of the coil overhanging the core are more exposed to the currents of oil than are the relatively inaccessible and remoter portions of the coil between the core legs and in the structure of this invention these exposed ends act to increase and distribute the cooling effect of the oil over the entire coil.

The coil C is built up of a series of windings W with their convolutions insulated from each other, forming vertical elliptical walls or sleeves, separated by vertical oil ducts D between spacing strips S. Toward the ends c of the coil these spacing strips S become progressively thicker so that the windings are spaced further apart at the ends and spread out to give ventilating ducts increasing in size toward the ends as indicated at 5, 6 and 7 (Fig. 3) and the overall dimension of the coil will increase on each side toward each end as indicated on the drawing by a b c (Figs. 1 and 3). The larger more exposed oil ducts at the ends will greatly augment the cooling effect of the oil on the coil rapidly receiving the heat from the coil conductors and flowing upward across the convolutions of the windings.

The conductors of the winding are preferably of flat or square wires wound side by side, (Fig. 4) each convolution 7 being made up of one wire 8 or a plurality of such wires wound together as a unit. The convolutions are insulated from each other, for instance by covering or winding a cord 10 around wires or convolutions, or both, or around alternate wires or convolutions, or both, and the entire coil is treated with a coating of varnish or insulating compound covering all the coil surfaces. The wires lying side by side present a maximum surface to the cooling fluid and are separated therefrom only by the layer of varnish or insulating compound so that the cooling fluid is substantially in direct contact with the surfaces of the wires.

With the extended coil ends of this invention a large part of the length of each convolution is thus exposed to increased

- cooling action and the copper wires being excellent conductors of heat rapidly conduct the heat from their less exposed portions between the core legs to the outer ends of the coil where the larger ducts are located. The symmetry and strength of the winding is maintained, because each convolution is wound in smooth oval form on curves of continuous gradually varying curvature of such large radius that the several convolutions are drawn close together and mutually sustain each other. The core legs may be of any desired section but for best efficiency are preferably deep in proportion to their width; i. e., narrow in the direction of the plane of the laminations, as shown.
- The extended coil ends of this invention also naturally accommodate themselves to a containing tank that is circular in section, the ends of the coils extending into that portion of the tank opposite the sides of the core. The cooling effect of the fluid is symmetrically and evenly distributed throughout the height of the coils, the ascending currents of oil flowing with increased velocity as they become heated. Each convolution is exposed to the cooling effect in substantially the same manner and different portions of the coil vary but little in temperature, so that the stresses between the parts of the coil due to relative temperature changes between the parts are minimized and the coil parts expand and contract together without relative shifting and do not tend to break apart. Each wire of each convolution of the coil is laid in a continuous curve without abrupt change or sharp corners which would cause the wire already laid to bend or buckle outward away from the other coils and loosen further when the winding on of the next convolution presses it in the opposite direction. In the coil of this invention the gradual curvature at all points permits the wires to be maintained in continuous close contact under constant tension with each convolution drawn snug against the one within it. All parts of the coil mutually support each other, and thus the coil is a unitary self-supporting whole with all parts held strongly and so preventing relative shifting and chafing and breakdown in service.
- I claim:
1. In a transformer the combination with a shell type core of a coil on the vertical middle leg thereof oblong shape in section and comprising successive windings with ventilating ducts between them substantially parallel to said leg, the ducts towards the ends of said coil being larger than those nearer the center.
  2. In a transformer, the combination with a shell type core of a coil on the middle leg thereof comprising successive spaced windings with their ends spaced further apart than their intermediate portions, thereby providing enlarged ventilating ducts between said ends.
  3. A coil for a transformer comprising successive windings of general elliptical form in section symmetrical around both axes and spread apart in the direction of one axis to provide enlarged ventilating spaces between said windings at the corresponding portions thereof. 75
  4. A coil for a transformer comprising successive windings of general elliptical form in section symmetrical around both axes and spaced apart in the direction of the major axis to provide enlarged ventilating spaces between said windings at their ends. 80
  5. In a transformer the combination with a core leg having one dimension in section longer than the other, of a transformer coil or coils of general elliptical form in section and having high tension and low tension spaced windings wound one within the other along said core and more widely separated at their ends to provide vertical ventilating ducts through said windings of increased size at said ends. 85
  6. In a transformer the combination with a core leg having one dimension in section longer than the other, of a transformer coil of general oval form in section and having concentric high tension and low tension windings along the length of said core leg, said windings being separated to provide vertical ventilating ducts through said windings, which ducts are of increased size at the ends. 90
  7. In a transformer the combination with a core leg having one dimension in section longer than the other, of a transformer coil of general oval form in section and having concentric high tension and low tension windings along the length of said core leg, said windings being spaced to provide ventilating ducts through said windings, which ducts are parallel to said core and of increased size at the ends. 95
  8. A transformer coil having a narrow aperture for a narrow core and conductors wound around said aperture in successive layers on continuous curves of varying curvature forming the ends of said coil into arch shape and comprising concentric high and low tension windings and having vertical insulating strips spacing adjacent windings to provide continuous vertical ventilating ducts throughout the length of the coil, said ducts being of increased size at the ends. 100
  9. In a transformer the combination of a vertical core leg, a plurality of surrounding conductor windings of bare varnished wire, said windings being concentric around the axis of said vertical core leg, the outer winding surrounding the inner winding, and having vertical ventilating spaces, the sides 105
  10. In a transformer the combination with a vertical core leg, a plurality of surrounding conductor windings of bare varnished wire, said windings being concentric around the axis of said vertical core leg, the outer winding surrounding the inner winding, and having vertical ventilating spaces, the sides 110
  11. In a transformer the combination with a vertical core leg, a plurality of surrounding conductor windings of bare varnished wire, said windings being concentric around the axis of said vertical core leg, the outer winding surrounding the inner winding, and having vertical ventilating spaces, the sides 115
  12. In a transformer the combination with a vertical core leg, a plurality of surrounding conductor windings of bare varnished wire, said windings being concentric around the axis of said vertical core leg, the outer winding surrounding the inner winding, and having vertical ventilating spaces, the sides 120
  13. In a transformer the combination with a vertical core leg, a plurality of surrounding conductor windings of bare varnished wire, said windings being concentric around the axis of said vertical core leg, the outer winding surrounding the inner winding, and having vertical ventilating spaces, the sides 125
  14. In a transformer the combination with a vertical core leg, a plurality of surrounding conductor windings of bare varnished wire, said windings being concentric around the axis of said vertical core leg, the outer winding surrounding the inner winding, and having vertical ventilating spaces, the sides 130

of which are formed by said bare varnished wire, oil adapted to circulate through said spaces, and an enclosing tank.

10. In a transformer the combination of a vertical core leg, a plurality of surrounding coils composed of windings of bare wire, insulating compound separating the several turns of each winding, said windings being concentric in relation to each other and said

core leg and the outer windings surrounding 10 the inner windings and having vertical ventilating spaces between successive windings the sides of which spaces are formed by said wire, oil adapted to circulate in the ventilating spaces in contact with the several turns of the wire, and an enclosing tank. 15

ROBERT V. BINGAY.
